SPECIFICATION forming part of **Design No. 25,001**, dated **December 24, 1895**

Application filed **May 9, 1895**. Serial No. **548,772**. Term of patent **7 years**.

To all whom it may concern:

Be it known that I, MAXMILIAN ERNST, a citizen of the United States, residing at Cleveland, in the county of Cuyahoga and State of Ohio, have invented and produced a new and original Design for Box-Covers, of which the following is a specification, reference being had to the accompanying drawings, forming a part thereof.

Figure 1 is a picture of a box-cover made according to my design. Fig. 2 is a central vertical section of the cover applied to the box.

The box-cover *b* is hollow and adapted to fit over the box proper *a*, and the design that constitutes the subject-matter of this appli-

cation consists, essentially, in the configuration or shape of the external surfaces of the sides and top of the hollow cover to form the bust of Washington, the first president of the United States.
